WILLIAM H. SMITH, OF NEWPORT, RHODE ISLAND.

Letters Patent No. 92,485, dated July 13, 1869.

IMPROVED VELOCIPED.

The Schedule referred to in these Letters Patent and making part of the same.

To all whom it may concern:

Be it known that I, WILLIAM H. SMITH, of Newport, in the county of Newport, and State of Rhode Island, have invented a new and improved Velocipede; and I do hereby declare that the following is a full, clear, and exact description thereof, reference being had to the accompanying drawings, making part of this specification, in which—

Figure 1, plate 1, is an elevation of one side of the carriage, having three wheels.

Figure 2, plate 1, is a front elevation of the carriage, showing both treadles and their adjustable guides.

Figures 3 and 4, plate 1, are views, showing a yoked standard, adapted for a single rear wheel.

Figure 5, sheet 2, is a view in detail, and partly in section, showing the manner of connecting the steering-lever to the reach, and of applying a spring to it.

Figures 6 and 7, plate 2, are views, showing the construction of one of the clutching-devices.

Figure 8, plate 2, shows an elevation of the rear guide-wheels, and the manner of connecting them to the reach.

Similar letters of reference indicate corresponding parts in the several figures.

This invention relates to certain improvements, which are applicable to either two-wheel or three-wheel velocipedes.

It consists—

First, in applying to the shaft of the driving-wheel two pulley-clutches, and also an adjustable guide-frame, and in providing such frame with rectilinear reciprocating treadles, which are connected, by cords or chains, to the said pulley-clutches, the latter being connected together by a cord or chain, all in such manner, that while the treadles and their frames can be adjusted at different angles, an alternate reciprocating motion, imparted to the treadles by the feet of the rider, will communicate a continuous rotary motion to the said drive-wheel, without the inconveniences attending crank-motion, as will be hereinafter explained.

Second, in the application of a spring to the steering-lever, in combination with a notched block, applied to the reach, whereby the said lever will be held positively in position, when it is adjusted in its notch, for guiding the machine in a straight line, as will be hereinafter explained.

Third, in a mode of applying a spring between the reach and the axle-standard of the rear supporting-wheel or wheels, so as to allow this axle to be turned either toward the right or left hand, for guiding the machine, and in providing the pivotal connection of said standard to the reach with a stop-pin for limiting its motion, as will be hereinafter explained.

To enable others skilled in the art to understand my invention, I will describe its construction and operation.

The front driving-wheel A, and its axle A', are rigidly connected, by means of a yoke-standard, C, to a front portion, E' of the reach E.

The rear wheel or wheels B, and axle B', are connected to the reach E, by means of a pivot, L, so that these wheels serve as the guide-wheels.

The lever G, which is pivoted to the reach E at G', and which underlies this reach, has its extremities forked; one fork embracing a grooved wheel, j, on an arm, h, of the spindle g¹ of the steering-lever g², and the other fork embracing a grooved wheel, s, on an arm, which is fast to the portion s² of the rear-wheel standard H.

The spindle g¹ of the steering-lever is passed through the reach E and its lower extension E', and upon this spindle, below the extension E', a rubber, helical, or other suitable spring, g, is applied, which is held in place by a nut, as shown in figs. 1 and 5.

Just in rear of the lever-spindle g¹, and fastened on top of the reach E, is a block, i, in which a notch is made for receiving a steering-lever, g², when this lever is in the position indicated in figs. 1 and 5.

The spring g operates continually to draw down the steering-lever, so that when this lever is in its notch, the spring will positively hold it therein.

The axle A' is made of sufficient length to receive upon it, on opposite sides of the wheel A, two clutch-pulleys, a a; also, the eye-bearings of a frame, in which two treadles, c c, work.

The guide-frame for the treadles consists of two pairs of parallel rods, b b, one pair being arranged on each side of the wheel A, and connected by eye-bearings to the axle A'.

The upper ends of the guides are connected together by a head-piece, b', which is centrally connected to a slide, d, that works on a segment, D.

The segment D is rigidly secured, at its front end, to the head of standard C, and extends backward and downward, in the arc of a circle, concentric to the axis of the axle A'.

The slide d is provided with a set-screw, d', for securing it rigidly to the segment D, according to the invention it is desired to have the treadle-guides b b b b.

The treadles c c are connected to their respective guide-bars b, by means of tubes, so that these treadles will slide up and down freely.

To both treadles, rods c c are secured fast, which rods extend downward, and are connected, by their lower ends, to the clutch-pulleys a a, by means of cords or chains e, which pass once or twice around these pulleys, in annular grooves therein, and are attached to the pulleys, so as to turn them in one direction, when the treadles are depressed.

A cord or chain, e, is passed over pulleys p, which are arranged at the upper ends of the inner guide-bars b b, and its ends carried around annular grooves made in the clutch-pulleys a a, and fastened to these pulleys a a, so that when one treadle c is depressed, the pulley a of the opposite treadle will be turned, so as to wind up its cord or chain e, and raise its treadle. By this

arrangement of cords and treadles, it will be seen that the clutch-pulleys α will receive an intermittent rotary motion in one direction, by giving alternate reciprocating motions to the treadles.

Each pulley α has an annular chamber in one end, as shown in figs. 6 and 7, and each pulley α is applied loosely upon its axle A. It is necessary to have each pulley turn loosely around its axle, in one direction, and to turn the axle when the pulley is turned in the opposite direction.

When the treadle of a pulley, α , is depressed, it is desired to have such pulley turn the axle A', and when the same treadle is raised, by depressing the treadle on the opposite side of driving-wheel A, it is desired to have its pulley turn loosely around its axle.

This is effected by means of a pawl, r , which is pivoted in the chamber in each pulley α , which pawl is connected, by a rod, r' , to a disk, r .

The pawl r' engages with the teeth of a ratchet-wheel, α' , fixed on axle A', when the pulley α is turned forward; but when this pulley is turned backward, the pawl is released from its ratchet-wheel, and, consequently, does not turn the axle A'.

In front of the steering-lever g , and pivoted at m to the reach E, is a lever, J, one arm of which extends backward and upward, as shown in figs. 1 and 5, to a position where it can be conveniently reached by a person sitting on the saddle F.

The other arm of this lever J is extended down through the portion E' of the reach, and curved forward, so as to form a shoe that will operate as a brake to wheel A, when the upper end of the lever is pressed upward. The brake, thus arranged, can be operated to check the progress of the carriage, with one hand, while the other hand may be grasping the handle of the steering-lever.

The saddle F is supported upon a semi-elliptical spring, f , which is secured in a suitable manner upon the reach E. I am aware that saddles for velocipedes have been pivoted at their front ends, and sustained by springs under their rear ends, but I am not aware that a saddle has ever, before my invention, been mounted wholly upon a spring, as shown in fig. 1. This arrangement entirely relieves the rider from shocks, and affords him an easy-riding seat.

The standard of figs. 1 and 8 is adapted for two guide-wheels, B B, and the standard H, of figs. 3 and 4, is adapted for a single guide-wheel; and as the upper connecting-portions of these two standards are precisely alike, it is obvious that one standard can be substituted for the other, according as it may be desired to have a bicycle or a tricycle.

From the upper end s^2 of the standard H, rises a cylindrical rod, or spindle, L, which is passed loosely through a semi-elliptic spring, t , through the reach E, and through a box, l , and provided with a nut on its upper end.

The spring t is between the reach and the upper end s^2 of the standard H, and affords elasticity to the reach, and comfort to the rider, and also increases vertically the bearing for the rod L of the said standard.

The rear side of the fixed box l is open; and from the rod L a stop-pin, t' , protrudes through said-opening, and serves, by its striking against the box l , to prevent the standard H from turning too far around, while steering the carriage.

Vertically, the opening through box l should be such as will allow the reach to play up and down freely on its spring t .

Having described my invention,

What I claim as new, and desire to secure by Letters Patent, is—

1. Clutch-pulleys α , applied to the axle A' of the driving-wheel A, and operated by means of cords and pulleys, and reciprocating treadles, which are applied to adjustable guides b , substantially as described.

2. The adjustable treadle-guides b , pivoted to axle A', at their lower ends, and connected at their upper ends by a slide, d , and screw d' , to a segment, D, substantially as described.

3. Spring g , applied to the steering-lever, substantially as described.

4. The spring t , applied between the reach E and pivoted standard H, substantially as set forth.

W. H. SMITH.
